ABSTRACT

This invention relates to a framed structural member for use as pillars, beams, girders and the like in buildings, vehicles and the like and also to a board structure for use in floors, walls, partition walls and the like.

**FRAMED STRUCTURAL MEMBER AND BOARD
STRUCTURE COMPOSED OF SHORT TIMBERS
ASSEMBLED**

BACKGROUND OF THE INVENTION

Generally, ordinary long timbers used as a structural member such as pillars, beams, girders, etc., take much labor and time to transport and handle. Moreover, they are smaller in strength than members for steel frame construction, and in consequence it conventional practice to increase the sectional area of the structural member in order to increase the strength of the structure. On the other hand, laminated wood or so-called laminated timber provided by laminating short timbers by use of a bonding agent is also well known. Although laminated wood is wood improved in quality by removing warps, cracks, etc., inherent in wood, it nevertheless has the same disadvantage of inconvenience in transport and handling as is the case with long timbers, and furthermore because it uses a bonding agent in connecting the short timbers, the laminated wood is not free from an ageing effect with lapse of time and is in adhesive force, which, in turn, reduces the strength of the laminated wood, thus being rendered unfit for long use as a structural member.

Also, it is a generally established knowledge that board structure such as formed in wooden walls, floors, etc., in buildings, vehicles and the like has heretofore been composed, in an adhesively connected form, of sawn board, plywood, hardboard, particle board, and the like. But board structure such as formed in floors, walls, partition walls and the like constructed of these materials is highly deficient in strength and, hence to obtain a structure of high strength, it is necessary to increase the thickness of board. The increase in the thickness of board involves an increase in weight, which, in turn, naturally reduced workability in construction work and leads to an increase in damage to the external angle portion and corner portion of the structure during construction. In addition, the manufacture of the aforesaid plywood and saw board involves the added disadvantage of producing a large quantity of waste timber. Also, laminated wood or so-called laminated timber produced by laminating and connecting short timbers by means of an adhesive is well known, but this laminated wood is not only expensive but laminated layers are liable to come off in exfoliated pieces. This is because the adhesive used in the laminated wood is subjected to an ageing effect with time and is reduced in adhesive force and strength, although the laminated wood has considerable strength for some time after manufacture. Furthermore, since the laminated wood makes it necessary to manufacture the wood considerably large in length and width for the purpose for which it is used as walls, floors, partition walls, etc., it takes much time and labor to transport and handle the material.

Short timbers such as mosaic parquet are also well known in the case of a floor material. The mosaic parquet is generally used for purposes of heat and cold reserving or of facing in rooms, and offers no difficulty in point of transport but has the disadvantage of being complicated in the method of working. Namely, when it is used in the construction of a floor surface of concrete structure, cement mortar backing has to be laid on the concrete floor surface and this laying of backing requires a highly skilled art, and curing of this backing

requires a long period of time. In addition, when this mosaic parquet is used in the floor surface of a general wooden house, the conventional method of construction has the disadvantage that concealed backing as such plywood, particle board or the like has to be laid on a floor joist. Furthermore, although a surface finish of bricks, tiles or the like over the concrete backing as a means of improving the appearance of a wall surface, floor surface, etc., is also well known, the disadvantage of such a surface finish not only requires expensive scaffolding and a large number of working days but also involves the danger that the tiles used will come off during and after construction and a tendency that the bricks and tiles will crack and fall in exfoliated pieces.

SUMMARY OF THE INVENTION

Hence the present invention has for its primary object the provision of a framed structural member for use in pillars, beams, and girders employed in buildings, vehicles and the like in which structural member the disadvantages of the nature of prior known structural members as hereinbefore stated are removed.

The invention also has for another object the provision of a board structure such as floors, walls or partition walls in buildings, vehicles or vessels and the like which board structure is free from the disadvantages described above and has a decorative property, earthquake resistance, durability, heat and cold reserving properties.

A board structure therefore according to the invention is composed of two or more than two interconnected short timbers which short timbers have formed therein more than one hole, into which rods or/and pipes are inserted which rods or/and pipes are connected by couplings, box screws and the like.

Additionally, the present invention provides an assembled board structure composed of at least two pieces of wooden brick, each brick being formed of square short timber which has on at least two sides of the four sides thereof more than one groove, the two pieces of brick being interconnected by inserting at least one of first and second coupling blocks into the groove.

Furthermore, the present invention provides a board structure composed, in combination, of at least two pieces of brick, the brick being formed of square short timber which has on at least two sides of the four sides thereof more than one groove and on one of the sides at least more than one through hole, the two pieces of brick being interconnected by inserting one or both of first and second coupling blocks and inserting rods or pipes through the through holes.

BRIEF DESCRIPTION OF THE DRAWINGS

These and other objects and advantages of the invention will become more apparent from a perusal of the following description of embodiments of the invention taken in conjunction with the accompanying drawings, in which FIGS. 1 to 8 show a framed structural member and FIGS. 9 to 16 show a board structure.

FIG. 1 is a fragmentary perspective view showing short timbers connected to each other by couplings and a cover fixed to the end of a short timber;

FIG. 2 is a front view of a short timber adapted to be connected by couplings;

FIG. 3 is a perspective view, broken in part, of the short timber;

FIG. 4 is a longitudinal sectional view showing the two short timbers interconnected by couplings;

FIG. 5 shows an embodiment different from that in FIGS. 1 through 4, and is a perspective view, broken in part, showing short timbers connected to each other by forming cutaway portions in the short timbers;

FIG. 6 is a front view showing the state of the short timbers being connected to each other by the same connection method as that in FIGS. 5;

FIG. 7 is a fragmentary front view diagrammatically showing an embodiment of the framed structural member of the invention in a pillar, groundsill and beam;

FIG. 8 is a perspective view, broken in part, of a short timber different in shape from that in FIG. 3;

FIG. 9 is a fragmentary perspective view of an embodiment of the board structure of the invention in a wall, the view showing the structure with some of the short timbers removed from the structure and broken clearly showing the state to show connection and assembly of the wooden bricks;

FIG. 10 is a sectional view taken on line I - I of FIG. 1;

FIG. 11 is a perspective view showing a part of FIG. 9, which view shows a backing member, plinth, and coupling block, broken in part;

FIG. 12 is a perspective view, broken in part, of the wooden brick that is used to construct the board structure;

FIG. 13 is a front view of the wooden brick similar to that in FIG. 13;

FIG. 14 is a sectional view taken on horizontal line II — II of the wall in FIG. 9, said view showing the wall

FIG. 15 is a fragmentary perspective view of an embodiment of the board structure in a partition wall; and

FIG. 16 is a perspective view of an embodiment of the board structure in a floor with some of the bricks removed from the floor and broken in part.

DETAILED DESCRIPTION OF PREFERRED EMBODIMENTS

Example 1

A description will now be made of the structural member shown in FIGS. 1 through 8.

The framed structural member constructed according to the invention comprises a pillar, stake, beam or girder is preferably a prismatic short timber chiefly square (regular square, rectangular) in crosssection, but depending upon the purposes and modes of use, may be formed into a polygonal, round, and any other suitable shape. The member is composed of more than two short timbers of the kind described above by connecting the timbers to each other by means of rods or/and pipes inserted into the short timbers. In the embodiment, a description will be made of a connection structure and a connection method of two prismatic short timbers.

In FIG. 1 is shown two interconnected prismatic short timbers 1 and 1a square in section. A description will be made of portions designated at 31, 32 and 33 other than the portions showing the state of connection of these short timbers 1 and 1a. And, into each of the short timbers 1 and 1a shown in FIG. 1 a plurality of rods 2 and 2a each are inserted, which rods 2 and 2a

are connected by couplings 3, and the short timbers 1 and 1a are connected by connection through the couplings. FIG. 1 shows those short timbers, partly broken, and the rods 2 and 2a cut off, so that the state of the rods 2 and 2a being connected by the couplings may be readily understood and the couplings 3 and the rods 2 and 2a received inside the short timbers may be clearly seen.

Now, a description will be made in FIG. 2 and others 10 subsequent thereto with reference to the respective shapes of the short timbers 1 and 1a, couplings 3, rods 2 and 2a shown in FIG. 1. First, only short timbers square in section are shown in FIGS. 2 and 3, and the numeral 4 in the figures designates through holes bored in the longitudinal direction of the short timber 1. These through holes 4 are intended to receive the afore-stated rods 2 thereinto, and five through holes are bored in this embodiment. The holes 4 each are enlarged in diameter in both end areas of the short timber 20 1 so as to form a large diameter portion 5 therein. The large diameter portion 5 is intended to receive said couplings 3 therein. Next, a description will be made of these couplings 3 in conjunction with FIGS. 1 and 4. FIG. 4 shows the rods 2 and 2a connected by the couplings 3 and the short timbers 1 and 1a connected by the rods thus connected. The coupling 3, as shown in FIG. 4, is formed of metal and synthetic resin, and is formed into a cylindrical shape having a partition wall 7 in the center thereof and open at both ends. The outer diameter of each of the open ends of the coupling 25 3 is formed slightly smaller than the aforestated large diameter portion 5 of the short timber 1. And both side portions of the partition wall 7 in the center of the coupling have internal threads 6 and 6 cut. Next, a description 30 will be made of the rods 2 and 2a in the form of a reinforcing member with reference to FIGS. 1 and 4. These rods 2 and 2a are made of the same material as that of which the coupling 3 is made, and function as reinforcement, and accordingly they may be either rods or hollow pipes. In the case of the hollow pipes, they permit the passage of gas or liquid therethrough. This reinforcing member may be called simply a rod in this specification as the case may be. The rods 2 and 2a are formed in both end areas with external threads 8 and 8a, and these external threads are screwed into the internal threads 6 and 6 of the coupling 3. And in the embodiment in FIG. 1 the length of each of the rods 2 and 2a, in consideration of the partition wall 7, is conveniently made slightly shorter than the length of each of the short timbers 1 and 1a into which they are inserted. Accordingly, if the rods 2 and 2a are so made in length, it is only necessary to make the rods 2 and 2a the same in length when the short timbers 1 and 1a are formed 40 45 50 55 the same in length.

Next, the framing of the structural member in this embodiment will be made more apparent by describing an example of the method of connecting the short timbers 1 and 1a by the couplings 3 with reference to FIGS. 1 and 4. First, the rods 2 are inserted into the through holes 4 of one short timber, and the external thread 8 of each of the rods 2 is caused to project into the large diameter portion 5, a washer 9 is fitted over the external thread 8 and the washer 9 is inserted into the large diameter portion 5 and placed on the bottom 10 thereof. Then, a lock nut 11 is threadedly fitted over said external thread 8 to thereby bring the lock nut into contact with the lock washer 9. Thereafter, the cylind-

drical coupling 3 is threadedly fitted over the external thread 8 of each of the rods 2, and the lock nut 11 is brought into contact with one end of the coupling 3 to thereby bring the coupling 3 into firm engagement with the lock nut 11. By so doing, the coupling 3 and the rod 2 are securely connected to each other by the action of the lock nut and lock washer 9. As shown in FIG. 1, all the five rods 2 are securely connected by the same method. Next, another rod 2a is inserted into a through hole 4a of another short timber 1a similar to the aforesaid short timber 1, said through hole 4a corresponding to that 4 of the aforesaid short timber 1, an external thread 8a of the rod 2a is caused to project into that large diameter portion 5a of the short timber 1a which corresponds to the large diameter portion 5 of the timber 1, a washer 9 is fitted over the external thread 8a, a lock nut 11a is threadedly fitted over the thread 8a and further the external thread 8a is screwed into said coupling 3, whereupon the rod 2a and coupling 3 are firmly connected by the lock nut 11a and the like. This is the same proceeding as that taken in fixing the coupling 3 to the rod 2 inserted into the timber 1, and the parts used are also the same, and the fact that a plurality of rods 2a as shown in FIG. 1 are all fixed is also the same. In this manner, as shown in FIGS. 1 and 4, the short timber 1 and another short timber 1a are firmly connected. The description above has been made of the case in which two short timbers 1 and 1a are connected, and in the case in which the short timbers are used as framed structure as pillars and stakes, any number of short timbers of suitable length, as shown in FIG. 7, depending upon the lengths of the pillars and stakes, are connected to each other by the connection method mentioned above or a connection method to be later described.

Next, a description will be made of another embodiment of the method of connecting short timbers with reference to FIGS. 5 and 6. In the figures, members and parts used in the same manner as those of the embodiment shown in FIGS. 1 through 4 are indicated by the same or like reference characters for ready understanding. Also, FIG. 5 is a partly cutaway view for the same reason as FIGS. 1 and 3. In FIGS. 5 and 6 is shown the state in which the short timbers 1, 1a and 1b are connected to each other by the rods 2, 2', and 2b. The short timbers 1, 1a and 1b are respectively formed with the same through holes 4, 4', 4a, 4a', and 4b, 4b' as those in the preceding embodiment, and in this embodiment also the through holes are formed at five points. Short timbers 1, 1a and 1b are formed at the suitable points thereof with recessed cutaway portions 13, 13a and 13b respectively. The cutaway portion 13, 13a and 13b are formed with through holes 4', 4a' and 4b' respectively. Rods 2, 2', 2a, and 2b inserted into those through holes 4, 4', 4a, 4a' and 4b, 4b' are formed in each end area thereof with external threads in the same manner as the rods in the preceding embodiment. Next, a description will be made of an example of the method of connecting the short timbers 1, 1a and 1b in this embodiment, and the structure of this embodiment will be illustrated. First, the rod 2' is inserted into the through hole 4' of the short timber 1. In this case, as apparent from FIG. 6, the through hole 4' is separated right and left as the cut-away portion 13 and each one rod 2' is inserted into the right and left of this through hole 4', namely two rods 2' in all are inserted into the right and left through holes 4'. For con-

venience, the left side and the right side in FIG. 6 are called the right and the left respectively. The external thread 8 formed in the end area of each rod 2' is caused to project into the cutaway portion 13 of the short timber 1, a washer 14 is fitted over the external thread 8 and clamped with a nut 15 and a split pin 16 is fitted to thereby fix two right and left rods 2', 2' to the short timber 1. In this case, if a box washer 14' having holes to permit the insertion of each rod 2' therethrough was inserted into the cutaway portion 13 before the insertion of each rod 2', the washer 14 functions effectively not only as a washer but also as a reinforcing member. Next, the rods 2 are inserted into the rods 2' are inserted into the respective holes 4 of the short timber 1, couplings 3 and others are fitted over the external threads 8 of the rods 2 in the same manner as in the preceding embodiment, the rods are connected by the couplings and others to the rods 2a, and the rods are connected to the rods 2b in the same manner. When the short timbers are in this state, a part of the rod 2' and the rods 2a project to the left of the short timber 1 in FIG. 6 and a part of the rod 2' and a rod 2b other than those projecting to the left project to the right. Thereupon, the rod 2' projecting to the left is inserted into the through hole 4a' of the short timber 1a and the rod 2a is inserted into the through hole 4a to thereby bring the timbers 1 into contact with the timber 1a. The external thread portion 8' in the left end area of the rod 2' that is positioned on the left side of the short timber 1 is projected into the cutaway portion 13a of the timber 1a, and the rod 2' on the left side is connected by the washer and the nut 15a to the short timber 1a in exactly the same manner as the short timber 1 and rod 2' are connected. In exactly the same manner as that, the short timber 1b is connected to the right side of the short timber 1. As described above, the portions designated at 17 in FIG. 6 are shown adapted to be connected by the couplings 3 and the like, but they all may instead be connected by the cutaway portions and nuts, etc. Also, for the convenience of description, different reference characters have been used in explaining the rods, short timber, and the through holes and the cutaway portions formed therein respectively, which may of course be used not only in the same shape but also in various shapes and sizes. The description above has been made with respect to the case in which three short timbers are connected. It should be understood however that a suitable number of short timbers can be connected in like manner.

Now, a description will be made of the case in which the structural member is used as pillars and stakes in buildings and constructions with reference to FIGS. 7 and 8. In the figures, members and parts the same as or similar to the short timbers and the previously described members and parts are designated by the previously used reference characters to which alphabets are attached. In FIG. 7 the numeral 18 designates a concrete foundation laid on the ground 19, and the numeral 20 designates a ground sill placed on the foundation 18. A short timber 1c constituting this ground sill 20, as shown in FIG. 8 (FIG. 8 is also a partly cutaway view), is formed with longitudinal through holes 4c and large diameter portions 5c in the same manner as the short timbers 1 shown in FIGS. 2 and 2, and is further formed transversely of the timber 1c formed with a suitable number of through holes 21 in such a position as that in which they will not intersect through holes 4c.

Now, referring to an assembly method, the lower part 23 of each of anchor bolts 22 is first embedded in and fixed to the foundation 18 and then a short timber 1c is laid horizontally on the foundation 18 by fitting suitable holes 21' of a plurality of through holes 21 of the short timber 1c over the respective upper parts 24 of the bolts 22. Thereafter, another short timber 1d and still another are successively connected by the rods 2 and couplings 3 as described in the preceding embodiment until finally the groundsill 20 is completed. Then, the through holes 4e of a short timber 1e which constitutes a pillar 25 and which is similar to that shown in FIG. 2 is fitted over the upper parts 24 of the anchor bolts longitudinally in right-angle relation with respect to the upper parts 24. In this case, it is to be understood that the through holes 21' of the aforesaid timber 1c and the through holes 4e of the timber 1e which constitutes the pillar 25 are in axial alignment with each other and that the groundsill 20 and the pillar 25 are formed to have no irregularities on their outer surfaces 27 and 26. The short timbers 1e and 1c need not be connected by couplings. In this case, the through holes 4e in the timber 1e need not be formed in the respective lower end portions thereof with large diameter portions. Next, a short timber 1f is connected to the top of the timber 1e by use of rods 2f by the coupling connection method described in the first embodiment, and thus the pillar 25 is constructed. The number of short timbers necessary for construction of the pillar 25 depends upon the height of the pillar 25. A short timber 1g in the uppermost step is connected to a short timber 1h, that forms a beam 28, at right angles with respect to the short timber 1h, and this timber 1h is the same short timber 1c as that which forms said groundsill 20, and the rods 2g inside the short timber 1g that forms the uppermost step of the pillar 25 are projected through the holes 21h of the short timber 1h which makes up the beam 28, and the beam 28 and the timber 1g are connected by nuts 29 and washers 30. It will be readily understood from the figure that the rods 2g used herein are longer in length than the other rods 2f. The short timbers that from the beam 28 can also be successively connected to one another by the aforesaid connection method by use of the rods 2 and couplings 3 until finally the beam 28 is completed. In the embodiment illustrated in FIG. 7 connection is made by the couplings, etc., shown in FIGS. 1 and 4, but it is to be understood that the connection means shown in FIGS. 5 and 6 can also be employed in the embodiment. It is clear that of the short timbers shown in FIG. 7 all the timbers other than those designated by the character 1c and 1h may be used in the same shape as that in which those shown in FIGS. 2 and 3 were used. The connection in the embodiments described and illustrated above is made by use of couplings, lock nuts, lock washers or slotted nuts and the like, but this is a mere example and it is clear that not only other conventional types of connection means may be used in the connection but also, depending upon the method of construction, connection by use of the couplings alone without using the lock washers is possible. Also, if connection is made after a metal or other elastic plate the same in horizontal sectional shape as the short timber has been sandwiched, where necessary, between the respective contact surfaces of the short timbers, the contact surfaces and contact parts of the timbers can be increased in strength. Furthermore, it is desirable to conceal the

cutaway portion for the couplings and the clamped part of the couplings from outside by use of a cover made of the same wood as the short timber. For example, when the timber as seen in FIG. 1 is positioned at the ends of the beam made of the short timbers, a cover 31 is formed so as to conceal the couplings and clamp fittings 30 from outside, the cover being provided with cavities 32 to receive the couplings and means 33 to connect the short timbers.

In the three embodiments described above, the framed structural member according to the invention has been illustrated by referring chiefly to the method of assembling component members, but it should be noted that the order of assembly may be suitably determined in the execution of construction, depending upon the structures to be made. Also, the short timbers generally represent pillarlike timbers (square timbers) having a length of more than 10 cm and less than 100 cm, but the short timbers used in the invention are not limited to those having that size but the term is generally so as to include a general timber of long length.

As described above in detail, the structural member according to the invention is made up of short timbers connected by rods and suitable connection means, and hence it is formed with such numerous connection portions that even if impact force and load from outside are applied to the structure, such force and load are dispersed and absorbed at each connection portion. Accordingly, the structure as a whole has greatly increased elasticity and provides a durable structure having far greater elasticity than that made up of conventional long timbers. Moreover, the structure of the invention, by a combination of timbers and rods, can perform a function similar to a steel concrete structure and is optimum as a framed structural member for use in buildings, structures, vehicles or vessels and the like and is not reduced in strength by the effect of time as is the case with a conventional glued laminated timber.

Also, the structural member of the invention is made up of timbers and metal rods or rods of rigid material, and particularly in the embodiments described above a framed structural member is provided in which a combination of timbers and metal rods makes it possible to compensate the disadvantages of timber by the metal rods and those of the metal rods by the timber and which is increased in strength by the maximum use of the advantages of timber and metal properties. On the other hand, the conventional framed structural member made of long timbers required that the member to be used be suitably changed in size and sectional shapes of pillars, beams, etc. in accordance with strength required. Namely, under heavy load, a timber large in sectional area must be used. However, the structural member according to the invention makes it possible to obtain an economical and functional framed structure without changing the sectional shape of the structural member by suitably selecting the quality of material for the rods or pipes to be inserted into the short timbers and the diameters of the rods or pipes, using rods high in strength where great strength is required, and using rods of suitable material at points where less strength is required. In addition, the invention can conveniently provide a structural member very economically in that the invention makes it possible to utilize as the short timber of the invention those odds and ends of timber

which have heretofore been discarded as scrap wood.

Example 2

A description will be made of a board structure constructed according to the invention shown in FIGS. 9 through 16.

The reference characters in these figures are used independent of the preceding embodiments in FIGS. 1 through 8, and hence they have nothing common to those in the preceding embodiments. Of course, the characters are common to FIGS. 9 through 16. The structure in this Example 2 is concerned with board structure used in floors, walls, partition walls, etc., in structure, buildings, vehicles or vessels, etc.

Next, a description will be made of embodiments of the invention with reference to the drawings. The embodiments show the cases wherein the board structure of the invention is used in walls, partition walls, guard rails and floors. In the drawings concerning the embodiments, the walls, partition walls, and floors are shown in the state of the walls, partition walls and assembled in part. The framing of the board structure of the invention will be illustrated by referring to the course of assembly in which the members chiefly making up the walls, partition walls and floors are assembled in accordance with the drawings. But the order of assembly of the board structure of the invention is not limited to the order of assembly in the embodiments to be described hereinafter.

FIGS. 9 through 14 show the cases wherein the interconnected board structure forms a wall. FIGS. 9, 11 and 12 are partly cutaway views for clearly showing the inside, and FIG. 9 further shows the state of the wall in which some of the wooden bricks making up the wall are removed from the wall assembly. In FIGS. 9, 10 and 11, the numeral 1 designates a plinth that is used as a base board or base. This plinth 1 is provided thereacross with a suitable number of through holes 2, said through holes being enlarged in diameter in the lower part of the plinth 1 so as to form a large diameter portion 3 therein. And a linear projection 4 is formed on the top of the cut in the end areas thereof are first inserted into the through holes 2 of the plinth 1 so that the external thread part 5 of the rods or pipes 6 may be positioned in the large diameter portion 3. In the large diameter portion 3 are fastened a suitable washer and a nut 7 to the external thread part 5 to thereby connect the rods or pipes 6 to the plinth 1. The length of the rods 6 may be suitably determined in accordance with the height of the wall 8 to be completed, and short pipes may be connected in the manner as will be described hereinafter. The plinth 1 into which the rods 6 have been inserted and to which the rods 6 have been connected may be keyed to backing members 99 by a suitable means such as for example a bonding agent 40 in FIG. 9 or bolts and nails 10 in FIG. 11. What is designated by the numeral 1' in FIG. 9 is also a plinth similar to the plinth 1, and rods 6 are inserted likewise into the plinth 1' and fixed. And one side of the plinth 1' is brought into contact with one side of said plinth 1 and connected to form a corner part. At this time, in order that the plinths 1 and 1' may be well adapted to be jointed to each other, the sides of the plinths 1 and 1' that come into contact with each other are cut off to form inclined planes. This is apparent also from FIG. 8.

Next, wooden tilelike or bricklike members (hereinafter called simply wooden bricks) are fixed to the plinths 1 and 1'. A detailed description will be made of the wooden bricks in FIGS. 12 and 13. As shown in FIGS. 12 and 13, the brick 11 is formed of a boardlike short timber worked in the manner later described, and the configuration of the wooden brick is such that grooves 14 and 15 are respectively formed in the center of the sides 12 and 13 or along the sides of the centerline, and each groove communicates with the other. Incidentally, the numerals 12 and 13 designate two opposing sides. Accordingly, in this embodiment, the wooden brick is formed on all four sides with grooves, which are biased from the center to one side and along which the brick forms sides 12 and 13 each having two edges, one thin and the other thick. Furthermore, a suitable number of through holes 16 and 17 are formed on said sides 12 and 13. In this embodiment, two holes are respectively formed on the sides 12 and 13. The groove 14 on the side 12 has such width and depth as to permit snug fitting of the projection 4 of each of the aforestated plinths 1 and 1' thereinto. The wooden bricks of the type described are fitted one after another over the aforestated rods 6 through the holes 16, and one groove 14 is fitted over the respective projections 4 of the plinths 1 and 1'. In this manner, as shown by 11a and 11a' in FIG. 9, all the wooden bricks in the first step row are fitted.

For the convenience of description in the specification, aforestated, when the bricks are shown assembled into a wall (FIGS. 9 through 11 and FIG. 14), reference characters designating those bricks are indicated by numeral 11 together with an alphabet. And the bricks to be fixed may all be used in the same shape but when the bricks 11a and 11a' in the first step row and the bricks 11b and 11b' in the second step row to be later described are assembled in a staggered relation as shown in FIG. 9, the bricks fixed at the end of the wall and those fixed in an external angle portion may be cut in halves and used. In order that no gap may be formed between the contact surfaces of the sides 12 of the bricks 11a and 11a' assembled into the wall, the length of each brick 11 and the position of each through hole are determined, and the through holes 16 are bored so that the axes of the through holes of those bricks assembled may be brought into alignment with the axes of the through holes 2 of the aforestated plinths 1 and 1', when the bricks are assembled. And the bricks so assembled may be fixed by nails 10 to a backing member 9 in the same manner as the plinths 1 and 1' (FIG. 11). And when the bricks 11a and 11a' are assembled into an external angle portion as shown in FIG. 9, it is only necessary to bring the respective back surfaces 19 of the bricks fixed to the external angle portion into contact with the pillar 18 set up in the external portion as shown in FIG. 14. Furthermore, in this case, each of the bricks 11a on one side to the external angle portion and each of the bricks 11a' on the other side to the external angle portion are cut off on one side so as to from inclined planed to thereby bring the inclined plane surfaces 20 and 21 into contact with each other as is the case with the aforestated plinths 1 and 1'. This is apparent also from FIGS. 9 and 14. Between the sides 12 and 13 on which the bricks 11a and 11a' assembled in this manner come into contact with each other there is provided a gap 22 by the groove 15 of each of the bricks, into which gap 22 a coupling block 23 is in-

serted as shown in FIG. 14. This coupling block 23 is preferably formed of a board which is the same in length as the bottom surface 24 (FIG. 13) formed by the groove 15 of each of the bricks, and is slightly smaller in its thickness than the width of the groove 15, and slightly smaller in width than the gap 22. By so doing, the coupling block 23 is made adapted to snugly fit into the gap 22. And it is apparent also from FIG. 14 that the gap 22 becomes an L-shape in horizontal section in the external angle portion and a square or a rectangular shape on other portions. Accordingly, it should be understood that, as shown in FIGS. 9 and 14, the shape of the coupling block 23 in the external angle portion is an L-shape in horizontal section and the shape of the block 23 in other portions becomes a square or a rectangular shape. As shown in FIGS. 9, 10 and 11, after the coupling block 23 has been inserted into all the gaps 22 of the bricks, other coupling blocks 25 are fitted into the respective grooves 14 on the top sides 12 of the bricks 11a and 11a'. In this embodiment, this coupling block 25 is a board which is formed slightly smaller in thickness than the width of the groove 14 formed on the respective sides 12 of the bricks 11a and 11a' and which has the same length as the width of a wall 8 to be completed. If formed in this manner, the coupling block 25, after having been inserted into the respective grooves 14 of the bricks 11a and 11a', is securely fixed inside the grooves 14 to provide a firm assembly. And these coupling blocks 23, 25 may be formed of a suitable material such as wood, synthetic resin or metal, and when it is necessary to distinguish one coupling block 25 from the other coupling block 23, the distinction is made by referring the block 23 as a first coupling block and the block 25 as a second coupling block in the description that follows. Incidentally, FIG. 14 is a sectional view taken on line II - III - VI of FIG. 9, and accordingly a second coupling block 25 should be shown, but is omitted for the convenience of explanation. Next, bricks in the second lowest step row from the bottom and designated by the numerals 11b and 11b' in FIGS. 9 through 11 are fixed, and this is carried out in the same manner as that in which those in the first step row were fixed, namely, the bricks are fitted over the rods 6 through the holes 16 and then the respective grooves 14 on the lower sides of the bricks 11b and 11b' are fitted over the second coupling blocks 25. In this case also, the upper sides 12 of the bricks 11a and 11a' in the first step row are brought into close contact with the lower sides 12 of the bricks 11b and 11b' in the second step row so as to leave no gap between the two upper and lower sides. Further, the same coupling blocks 23' as the first coupling blocks 23 used in fixing the bricks 11a and 11a' in the first step row are fitted into all the gaps formed by the grooves 15 of the bricks 11b and 11b'. The state of the first coupling blocks 23' having been inserted in this manner is clearly shown particularly in FIG. 11. In FIG. 11, the respective coupling blocks 25, 23' and 25' are shown broken for ready understanding. Furthermore, as shown in FIGS. 9, 11 and 14, second coupling blocks 25' similar to the second coupling blocks 25 are inserted into the grooves 14 on the respective upper sides of the bricks 11b and 11b'. The method of insertion is the same as that of insertion of the second coupling block 25. In entirely the same manner, bricks 11c and 11c' in the third step row, bricks 11d and 11d' in the fourth step row, ... and so on are successively as-

sembled. When, as shown in FIG. 9, the bricks are assembled in a staggered relation with respect to each other, the bricks at the ends of the wall surface and in the external angle portion of the wall are used in half the size of the bricks shown in FIGS. 1a and 13. This is also the same as was the case with the bricks in the first step row. Bricks in each step row may also be fastened by nails 10' and others to the backing member 9 in the same manner as the bricks 11a and 11a' in the first step row (FIG. 11). It should be understood that the number of steps of bricks to be assembled depends upon the height of a wall to be completed and the size of the brick. In FIG. 9, bricks 11e and 11e' are shown laid up to the fifth row. In this manner, the bricks are securely connected to one another by the first coupling blocks 23, 23', 23'' ... and the second coupling blocks 25, 25', 25'' ... inserted into the gaps formed by the grooves of the bricks and by the rods 6 inserted into the through holes 16. Furthermore, the first coupling blocks 23, 23', 23'' ... are so designated by use of different reference characters and as previously noted, all these coupling blocks are the same in shape and size and have nothing different in use. The same is the case with the second coupling blocks 25, 25' and other coupling blocks. Furthermore, as previously described, a description has been made of the bricks by referring to the bricks in the first step row as reference characters 11a and 11a', those in the second step row as 11b and 11b' and those in the third step row as 11c, 11c' ..., but these bricks can be used in the same shape and size as those of the bricks shown in FIGS. 12 and 13, except certain bricks used at the ends and in the external angle portion of the wall surface, and even those bricks at the ends and in the external angle of the wall surface are also the same in shape and size except certain of the bricks as described previously. A conventional edge keep board (not shown) is mounted to the bricks in the uppermost step row, and the edge keep board may be connected by rods, washers, nuts, etc. to the bricks in the uppermost step row. The first and second coupling blocks serve also to level and correct the irregularities on the surfaces of the bricks laid in layers and to provide uniformity. The through holes 17 formed on the sides 13 of the bricks are adapted to be used when the bricks are rotated through 90° from the state in which they are shown in FIG. 1 and when the bricks are longitudinally laid one over another, and need not be used in building the wall 8 shown in FIG. 9. Furthermore, if the edges of each brick are chamfered at 26 as shown clearly in FIGS. 12 and 13, the completed wall presents a solid and beautiful appearance.

It is not always necessary to use the plinths 1 and 1' and edge keep board described in the above embodiment, and in that case, it should be understood that neither the grooves 14 on the lower sides 12 of the bricks 11a and 11a' in the first step row nor the grooves 14 on the upper sides 12 of the bricks in the uppermost step row need be formed. And the length of the rods 6 need not be the same as the height of the wall 8 but shorter rods may be used for the assembly of the wall by connection by a suitable means such as couplings or stud nuts, and also the second coupling blocks may be provided not in the form of a long board as shown but in the form of a plurality of short boards connected. Furthermore, it is also possible to change the shape of grooves 14 and 15 of the bricks to provide grooves of T-shape and U-shape cross-section. The embodiment

shown above has been described with reference to the formation of the external angle portion, but this external angle portion is formed only when required, and when there is no need of forming the external angle portion, for example, as in the case of a simple form of a fence or guard rail, there is no need of plinth 1', bricks 11a' and 11b'. And it is apparent that when a re-entering angle portion is formed, it is only necessary to take the same proceeding as was required for constructing the aforesigned external angle portion. In addition, suitable changes may be introduced in a construction design by using various sizes of bricks in the construction of the wall.

FIG. 15 shows an embodiment of the structure according to the invention in a partition wall. FIG. 15 also is a fragmentary view similar to FIG. 11 and partly cut away and broken. By the partition wall herein referred to is meant the wall used in its two surfaces 27 and 28 in FIG. 15, and the wall referred to in the preceding embodiment is intended for use in its one surface alone. In FIG. 15, members and parts similar to those of the preceding embodiment are represented by like numerals. Differences from the preceding embodiment lie in firm connection by use of two parallel linear projections 4 formed in the plinth 1, two grooves 14 formed on the sides 12 of the bricks 11a, 11b, 11c, etc., two second coupling blocks 25 and 25'', and in the use of pipes 6 as a reinforcing member. An assembling method is the same as that described with reference to the preceding embodiment, and hence the method is omitted.

FIG. 16 is an embodiment of the structure according to the invention in a floor, the floor being shown broken in part. Like numerals are used in like parts having the same functions as those of the preceding embodiment. By the floor is meant a structure for use on a horizontal plane. In this embodiment also, the floor is built in substantially the same manner, and hence a detailed description is omitted. Since this embodiment is concerned with the floor, the point of difference from the preceding embodiment is that no plinth nor keep edge board is used but a joist 29 is mounted. Incidentally, in FIGS. 9 and 16, the wall and floor are shown in the state in which certain of the bricks constructing the wall and floor are removed therefrom, but this is for the purpose of clearly illustrating the bricks, couplings and rods in their assembled relation. It goes without saying that the completed wall and floor are of a flat board construction.

In the embodiments illustrated and described above are shown those in which the first and second coupling blocks are used. The use of both of the first and second coupling blocks would make it possible to achieve a sought-for object more positively, but even the use of either one of the two coupling blocks could lead to the attainment of a desired object. When either one block alone of the two blocks is used, the formation of grooves on the sides of the bricks may be limited to the groove into which the coupling block is actually inserted. Also, the use of either one of the first and second coupling blocks without using the rods or pipes would answer the purpose. In short, the rods, pipes, first and second coupling blocks may be used in a suitable combination in accordance with the purpose for which the structure of the invention is used. By the short timbers for making the wooden bricks referred to in the above description is generally meant a boardlike

timber having a length of more than 10 cm and less than 100 cm on one side but the term short timber of the invention does not limit the timber to this size but the term is used generically to include timber having greater size.

As described above in detail, the structure of the invention is an assembly of individual wooden bricks connected by coupling blocks and inserted rods, and hence even if the structure is subjected to an impact force at one point of the structure, it has no possibility of being affected by strain or the like because the impact force spreads over the whole surface of the structure, and is reduced by the connected parts of the structure. Accordingly, the structure of the invention of a plurality of connected wooden bricks is free from cracks and deformation due to strain. Besides, the structure of the invention provided by insertion of rods or pipes through the wooden bricks is necessarily increased in strength and particularly valuable as a durable and earthquake-proof construction. Moreover, being different from glued laminated timber, the structure of the invention is excellent in durability and earthquake resistance over a long period of time, and provides no possibility of the wooden bricks coming off in exfoliated pieces as was the case with conventional type facing bricks and tiles. Furthermore, the structure of the invention has the advantage that it is easier and quicker in construction method than any other structures.

Heretofore, plywood industry, lumbering industry have turned out a large quantity of odds and ends of timber as scrap wood. These short odds and ends have been used merely as fuel or a raw material for low quality pulp for use in corrugated cardboard or the like, but when such scrap wood is utilized in the structure of the invention, it can be not only effectively used in the structures shown in the aforesigned Examples 1 and 2, but also the structures thus obtained provide pillars, partition walls, floors, guard rails, etc., economically. And the use of short timbers can naturally reduce the production of scrap wood due to odds and ends of wood to a minimum and can provide pillar-shaped or board-shaped structure which is capable of being assembled into any desired size depending upon the number of short timbers used irrespective of whether the structure is a stake or wooden bricks and which has satisfactory structural function. Also, the wooden brick of the invention makes it possible to obtain a structure of boardlike member of stately and solid beauty by applying suitable working to the edges and surfaces thereof, for example, relief, embossing or engraving or other working which serves also as facing. Also, the invention makes it possible to construct a sanitary and beautiful building having walls, partition walls, floors, etc., excellent in heat and cold resisting ability and ventilation by a combined use of a framed structural member obtained from Example 1 and a board-shaped member obtained from Example 2.

Furthermore, the invention makes it possible to make effective use of low grade wood, as described above, which is found to be of small utility value in large quantities in the raw wood producing districts and which has heretofore been deficient in adequate and efficient use because of defects such as bend, cracks, etc. unfit for the manufacture of plywood and timber. In addition, since the short timbers are easy to transport and handle, the structure of the invention is convenient in that the structure is manufactured with particular ease. Fur-

thermore, formation of through holes in the short timbers and bricks before they are seasoned can expedite the seasoning of the timber and bricks not only from outside but from inside, thus preventing those deformation, warps, cracks, etc., of timber that are usually produced during seasoning. The use of pipes as a reinforcing member for strengthening the structure of the invention makes it possible to permit the passage of liquid or gas therethrough to thereby provide wall and floor surfaces capable of functioning as an air-conditioning means or a fire-distinguishing means in time of a fire.

We claim:

1. A boarded structure for use as a wall, a floor and the like of a building said structure comprising:

a backing frame structure;

a plurality of interconnected board-like wooden blocks in assembly, each having a series of mutually perpendicular throughholes and at least one groove formed in each adjacent contiguous face of the blocks in assembly, said assembly being fixedly connected on said backing frame;

metal-tie means disposed in each of said throughholes to form a fastening connection between each adjacent ones of said blocks in assembly;

first coupling means for coupling the blocks together and disposed in each one of the slots successively defined substantially parallel, by the opposing grooves in adjacent contiguous faces of the blocks in a first direction of the assembly;

second coupling means for coupling the blocks together and disposed in the continuous horizontal slots successively defined substantially parallel, by the opposing grooves in adjacent contiguous faces of the blocks in a second direction of the assembly which second direction is substantially at right angles to said first direction.

2. The structure as claimed in claim 1 wherein each said metal-tie means has accessible connecting portions comprising cutaway sections vicinal to at least each ad-

3. The structure as claimed in claim 1 wherein each 5 said metal-tie means comprises a piped member for delivering fluid therethrough.

4. A boarded structure for use as a wall, a floor and the like of a building, said structure comprising:

a backing frame structure;

a plurality of interconnected board-like wooden blocks in assembly, each having a series of mutually perpendicular throughholes and two grooves formed in each adjacent contiguous face of the blocks in assembly, said assembly being fixedly mounted on said backing frame;

metal-tie means disposed in each of said throughholes to form a fastening connection between each adjacent ones of said blocks in assembly;

first coupling means for coupling the blocks together and disposed in each one of the two slots successively defined substantially parallel, by the opposing grooves in adjacent contiguous faces of the blocks in a first direction of the assembly;

second coupling means for coupling the blocks together and disposed in the two continuous horizontal slots successively defined substantially parallel by the opposing grooves in adjacent contiguous faces of the blocks in a second direction of the assembly which second direction is substantially at right angles to said first direction.

5. The structure as claimed in claim 4 wherein each said metal-tie means has accessible connecting portions comprising cutaway sections vicinal to at least each adjacent contiguous face of the blocks in assembly each connecting portion comprising a coupling means for coupling said tie means together.

6. The structure as claimed in claim 5 wherein each said metal-tie means comprises a piped member for delivering fluid therethrough.
